DESIGN FOR A WRITING INSTRUMENT HOLDING DEVICE

John L. Schoedler, Toledo, Ohio

Application November 21, 1933. Serial No. 49,809

Term of patent 14 years

To all whom it may concern:

Be it known that I, JOHN L. SCHOEDLER, a citizen of the United States of America, residing at Toledo, Lucas County, Ohio, have invented a new, original, and ornamental Design for a Writing Instrument Holding Device, of which the following is a specification, reference being had to the accompanying drawing, forming part thereof:

Fig. 1 is a side elevation of a writing instrument holding device showing my new design; and

Fig. 2 is a plan view of the device of Fig. 1.

I claim:

The ornamental design for a writing instrument holding device as shown.

JOHN L. SCHOEDLER.
